UNITED STATES PATENT OFFICE.

JOSEPH VON SERKEY, OF CHICAGO, ILLINOIS, ASSIGNOR OF THREE-FOURTHS
TO ROCKWELL KING, OF SAME PLACE.

WIRE-NAIL MACHINE.

SPECIFICATION forming part of Letters Patent No. 448,620, dated March 17, 1891.

Application filed June 13, 1890. Serial No. 355,378. (No model.)

To all whom it may concern:

Be it known that I, JOSEPH VON SERKEY, a citizen of the United States, residing at Chicago, in the county of Cook and State of Illinois, have invented a new and useful Improvement in Wire-Nail Machines, of which the following is a specification.

My invention relates to an improvement in the class of machines for manufacturing nails from wire in which the wire is straightened and fed automatically in desired lengths to the cutting-dies, there severed, (and pointed,) and then held for the upsetting operation by the reciprocating header to form the head for the next succeeding length to be fed and severed (and pointed) to produce a nail, the various mechanisms for performing the several operations being actuated in proper succession from the rotary power-shaft; and my improvement relates particularly to the kind of machine in the above-named class in which the wire straightening and feeding devices, and also, if employed, the barbing or roughening mechanism, are supported on a reciprocating carriage moved backward during the heading operation and while the wire is being held or clamped for the same to produce the barbing and straightening of the wire before the feeding.

Objects of my invention are to enable the machine to work continuously and produce nails rapidly without overheating the parts, which I accomplish by causing the backward movement of the straightening, feeding, and (when employed) barbing mechanisms (by which such friction strain is occasioned as to induce great heating of the parts if caused to operate with great rapidity) to be produced much more slowly than the feeding of the wire by the subsequent forward movement of the carriage supporting those mechanisms, and to provide a more durable and otherwise better machine for the purpose than any hitherto provided, both as to its general construction as an entirety and as to parts thereof.

In the accompanying drawings, Figure 1 is a plan view of my improved machine, shown with the wire to be manufactured by it into nails in a coil supported on a reel of novel construction and which may form an attachment

for my machine; Fig. 2, a side view of the machine as regarded from the lower end of the longer side of the sheet containing Fig. 1; Fig. 3, a view like that shown in Fig. 2, but presenting the opposite side of the machine provided with the angular rocking-head detail for producing the "quick" movement of the feed and the "slow" movement for straightening and barbing; Fig. 3^a, a side view showing the angular rocking-head detail in its highest position; Fig. 3^b, a similar view of the same in its lowest position; Fig. 4, a broken longitudinal section of the machine, showing it in its preferred position of inclination, whereby the reciprocating carriage and the header tend to operate by their own gravity, the former to effect the straightening of the wire, or straightening and barbing, and the latter to upset the wire to form the head; Fig. 5, a section taken at the line 5 of Fig. 2 and viewed in the direction of the arrow; Fig. 6, a section taken on the line 6 6 of Fig. 1 and viewed in the direction of the arrows; Fig. 7, a section taken at the line 7 of Fig. 2 and viewed in the direction of the arrow to show the holding-dies, the cutting-dies, and the sliding heads carrying them being removed. Figs. 8 and 9 are sections taken, respectively, on the lines 8 8 and 9 9 of Fig. 8 and viewed in the direction of the arrows. Fig. 10 is a perspective view showing my improved reel; Fig. 11, a section taken on the line 11 of Fig. 10 and viewed in the direction of the arrow; Fig. 12, a broken view in perspective of a detail of the reel. Figs. 13 and 14 show perspective views presenting different ends of the sliding-head detail for the cutting and pointing dies. Figs. 15 to 17, inclusive, are similar views of other details of the cutting and pointing die mechanism. Fig. 18 is a section taken on the line 18 of Fig. 9 and viewed in the direction of the arrow; Fig. 19, an enlarged view in front elevation of the upper holding or clamping die detached from the machine; Fig. 20, a side view of the same; Fig. 21, a section taken on the line 21 of Fig. 19 and viewed in the direction of the arrow; Fig. 22, a section taken on the line 22 of Fig. 19 and viewed in the direction of the arrow; Fig. 23, a diagrammatic view representing the guiding-surface, straightened out and en-

larged, of one of the knife-operating cams on the power-shaft; Fig. 24, a plan view of the straightening, feed, and barbing mechanisms on the reciprocating carriage as shown in Fig. 1, but enlarged; Fig. 25, a side view of the same regarded from the side at the upper end of the sheet; Fig. 26, a section taken on the line 26 26 of Fig. 24 and viewed in the direction of the arrows; Fig. 27, a section taken on the line 27 27 of Fig. 26 and viewed in the direction of the arrows; Fig. 28, a perspective view of a detail; Fig. 29, a section taken on the line 29 of Fig. 27 and viewed in the direction of the arrow; Fig. 30, a perspective view of the dovetailed slide detail carrying a horizontally-disposed wire-straightening roller; Fig. 31, a broken perspective view of a detail; Fig. 32, a view in rear elevation of a wire-straightening device on the reciprocating carriage; Fig. 33, a section taken at the line 33 of Fig. 32 and viewed in the direction of the arrow; Fig. 34, a perspective sectional view of the carriage-bed, the section being taken on the line 34 of Fig. 25 and viewed in the direction of the arrow; and Figs. 35 and 36 are perspective views of details.

As illustrated, the operating parts occupy the relative positions they assume just after a length of wire for a nail has been fed from the reel and severed by the cutting-dies and the latter have been part way retracted or separated, the clamping-dies tightened against the end of the coil of wire, the carriage supporting the feeding or barbing, and the straightening-rollers moved backward—that is, toward the reel—on the length of wire therefrom inserted into the machine, and the header is being advanced to upset the end of the wire so inserted and form the head for the next nail to be produced.

A is the bed of the machine, having extended horizontally from its feed end (hereinafter referred to throughout the description as the "rear" end of the machine) two parallel guide-rods r for the reciprocating carriage A', supporting the straightening and the barbing and feeding mechanisms, hereinafter more definitely described.

B is the rotary power or driving shaft supported in suitable bearings on the bed A near the "forward" end of the machine (or that opposite the feed end) and formed with a crank w , Fig. 4, near its center. On the shaft B, at opposite sides of the crank w , are secured, to revolve with the shaft, collars v or bosses in pairs, the members of which are separated by a space caused to incline around the shaft by the opposing contrarily-inclined surfaces of the collars, the space between one pair inclining in one direction while that between the other inclines in the contrary direction, the two said spaces affording, respectively, cams in the form of cam-grooves C and C', the line of each of which, if straightened out, would be as represented in Fig. 23, thus differing in inclination on opposite sides of a shorter slightly-inclined line v' , forming the

line at which the cam actuates a severing-die to cut the wire by a gradually-deepening cut, owing to the slight inclination of the line v' , thus preventing sudden "chopping off" of the wire and consequent strain of the machine.

On one end of the shaft B is an eccentric y , having its horizontally-outward-extending crank-pin y' (see particularly Fig. 3) provided with a washer y^2 , confined to slide in a guideway formed in one side p of a two-sided angle-bar D, the two sides p and p' of which form a right angle and may be connected by a hypotenuse bar p^2 , and the angle-bar D is pivoted at its angle to render it a rocking head to an arm p^3 , extending horizontally from a side of the bed A. In the side p' of the rocking angle-head D is a threaded bolt p^4 , extending lengthwise therein and confined against longitudinal movement in turning it, which may be done with a wrench applied to its head, and on the bolt p^4 in a guide afforded between the longitudinal margins of the side p' is a nut p^5 , having pivotally secured to its outer side one end of a link D'. From the nut p^5 the link D' extends along a side of the machine toward its rear end, where it is pivotally connected with one end of a horizontally-disposed lever D², fulcrumed between its extremities to the bed A and joined at its opposite end, in the manner hereinafter described, to the carriage A'.

The carriage A', which should be formed in one piece, is of general rectangular form as to its base u , (see Fig. 34,) with perforated ears u' and u^2 extending downward and outward from and forming a pair on each side near the opposite ends thereof, with their perforations in the opposing members of the respective pairs in line with each other to admit a guide-rod r through each. At the end of the carriage-bed u nearest the wire-supply it is provided with heads $t' t'$, extending lengthwise from the edge of such end to opposite sides of the center thereof, where it is recessed at t^2 to receive between the heads $t' t'$ a vertically-disposed pivotal wire-straightening attachment E, (see particularly Figs. 32 and 36,) hereinafter described, the heads $t' t'$ being longitudinally perforated to contain the journals for pivotally supporting the attachment E, in order that it may be turned for its adjustment through a vertical plane.

The straightening attachment E comprises in its preferred form a rectangular oblong frame t , (see Fig. 36,) supported in normally-vertical position in the recess t^2 in the edge of the carriage-bed u between the heads $t' t'$ on journals s^2 and s^3 , extending from opposite sides of the frame midway between its ends through the longitudinal perforations in the heads, which thus form journal-bearings. Inside the frame are longitudinal guide-grooves for slidingly-adjustable journal-bearings s^4 and s^5 , carrying straightening-rollers s and s' , which should be centrally grooved around their peripheries, as shown, and may

be adjusted with reference to each other by set-screws s^6 , extending against the roller journal-bearings through the ends of the frame (one, the upper, of which ends should 5 be removable, as shown, to permit ready access, as for removal or adjustment of the parts within the frame) and provided with jam-nuts s^7 . On the projecting end of the journal s^8 is secured a handle s^8 , extending 10 across a stationary vertically-disposed segmental rack s^9 , engaged normally by a spring-pawl s^{10} (see Fig. 24) on the handle.

Farther along on the bed u of the carriage are journaled the pair of stationary horizontally-disposed wire-straightening rollers q' , extending at their grooved peripheries into the path of the wire W at one side thereof, and on the opposite side of the path of the feed between the rollers q' is a similar roller 15 q in a slidingly-adjustable bearing q^2 , confined in a dovetailed guide-groove q^3 , extending transversely across the carriage-bed. The preferred form of the sliding bearing q^2 is most clearly illustrated in Fig. 30. In its extension q^4 is a rectangular opening q^5 , in which 20 is confined the head q^6 , having an eccentric pivot-pin q^7 of a horizontally-disposed handle q^8 (see Fig. 31) provided on its under side with a spring-pawl q^9 to hold the lever 25 wherever adjusted by engagement with a stationary horizontal segmental rack q^{10} . As will readily be seen, turning the handle q^8 actuates the eccentric head q^6 to force the sliding bearing q into closer or less close relation 30 (according to the direction of turning the handle) with the rollers q' , according to requirement, for straightening the wire in the direction lateral to that of its feed.

Still farther along on the carriage-bed u I 35 provide for use when the nails manufactured by the machine are, as is quite commonly the case, to be notched or barbed on their shank portions the horizontally-disposed relatively adjustable rollers o , serrated transversely 40 to form straight parallel teeth across their even peripheries entirely around the rollers. These rollers are journaled on opposite sides of the wire-feed line in bifurcated sliding bearings o' , (see Fig. 35,) confined in a groove 45 o^2 , extending straight across the bed u , and at the ends of which the sides of the bed are built out into box-shaped bearings o^3 , perforated in their ends, which are extended upward into tongues o^4 , having seats o^5 behind 50 them. The sliding bearings o' , carrying the barbing-rollers o , are confined in the groove o^2 by a rectangular collar o^6 , fitting around the tongues o^4 on the seats o^5 , and set-screws o^7 , fastened by jam-nuts o^8 , extend through 55 the perforated ends of the bearings o^3 against the sliding roller-bearings o' , and afford means for adjusting them in the groove o^2 with relation to each other. The collar o^6 is firmly held in place by the outward spring in the 60 tongues produced by the strain of the set-screws forced against the bearings o' , and it affords desirable means for its purpose, par-

ticularly by reason of the readiness with which it may be removed to permit access to the barbing-rollers o to enable them to be 70 withdrawn from the machine when not used or for sharpening their teeth or substituting other rollers for them, the regular form of the serrated peripheries permitting ready sharpening of the barbing-teeth.

At the end of the carriage-bed u , provided with the perforated ears u^2 , are the vertically-disposed rollers n , which, if employed for barbing the nails, are serrated like the rollers o . The rollers n are supported, similarly to 80 the vertically-disposed straightening-rollers s , in a frame n' , shown (see Fig. 26) in the form of a solid block having a vertical rectangular central recess formed with guides for journal-bearings n^2 (see Fig. 27) for the 85 rollers n , adjustable by means of the set-screws n^3 , secured by jam-nuts n^4 and extending against the bearings n^2 through the ends of the supporting-frame, the upper of which ends should be in the form of a removable cross-head, as shown, to permit ready 90 access to and adjustment of the rollers. For the purpose of increasing the frictional resistance against the rotation of the upper of the two rollers n and to prevent slipping thereof 95 against the resistance of the wire while feeding, I confine against its opposite sides dogs n^5 , pivoted to the front side of the frame n' between their extremities and connected at their upper ends by a screw n^6 , provided with a nut n^7 , the turning of which adjusts the upper 100 ends of the dogs with relation to each other, and thereby regulates the degree of pressure of the dogs at their lower ends against the said wheel n .

At one side of the block or frame n' (that presented in Fig. 26) it is somewhat enlarged, as shown at m^2 in Fig. 27, and provided with a recess m' deeper than a hollow head m , Fig. 28, confined within it and having its outer side formed with a flaring opening m^3 , assuming the form of a cylinder m^4 as it extends into the head. The head m receives the end of the lever D^2 , adapted in form to fit its recess.

The operation of the parts thus far described is as follows: As already stated, the relative positions in which the nail-producing parts are shown in the drawings (see particularly Fig. 1) present the clamping-dies 110 as proceeding to clamp the wire (from which a section has been previously severed by the cutting and pointing dies, which, as shown, are undergoing separation) to firmly grip it against the stroke of the reciprocating header, 115 which, as shown, is in process of advancing to perform its function. All these last-named parts and their operations are hereinafter more definitely described, though it will be understood that they are all actuated by the 120 rotation of the power-shaft B in the direction indicated by the arrow in Fig. 1 and suitably timed as to the order of their operations by their connections therewith. The car-

riage A' , therefore, with the devices it supports, having been advanced (to feed the length of wire cut off, as stated) by the gripping effect upon it of the barbing-rollers o n , which form the feed-rollers in the advancing movement of the carriage, is now moving backward, and in its backward movement the barbing-rollers throughout the length of stroke of the carriage A' are barbing or indenting the wire (held, as aforesaid, by clamping-dies near the end from which a section has previously been severed) and the rollers q q' and s s' are straightening it, the frame of the last-named rollers being adjusted to the angle required for insuring the straightening in a vertical direction of the wire. This backward movement of the carriage, which is materially assisted by its own weight when inclined, as shown in Fig. 4, is about one-third as fast (and thus comparatively slow) as its forward or feeding movement, the difference in speed being due to the action of the pivotal vertically-rocking angular head D , Fig. 3. This, with its immediately-actuating parts in the relative positions presented in the last-named figure, is obviously turned or rocked on its pivot p^3 , Fig. 1, in an upward (as to the arm p) and forward (as to the arm p') direction till the eccentric y and its pin y' with the rotation of the shaft B assume a position (see Fig. 3^a) wherein the crank-pin y' is at the angle of a right-angle triangle drawn from the center of shaft B to the center of the pivot p^3 , in moving toward which position the pin y' gradually slides the washer y^2 inward or in the direction toward the pivot-center p^3 in its guideway, provided in the arm p of the rocking head. This upward and forward movement of the head D , which proceeds during about three-fourths of each rotation of the shaft B , draws backward on the link D' , throwing the end of the lever D' engaging with the carriage in the opposite direction, and consequently also the carriage in such opposite or backward direction, to barb and straighten the wire.

It will now be understood that the purpose of forming the recess m' deeper than the hollow head m is to permit the latter to have some inward play in its containing recess, in order to yield as the length of the radius between the head m and the pivot-center of the lever D' changes in the movements of the lever toward and from its intermediate position at a right angle to the carriage. Thus with the three-quarters rotation of the eccentric y and pin y' , wherein they rock the head D , as stated, with the result described, the motion of such head is considerably slower (about one-third as fast) than when the said eccentric and pin are performing the other quarter of their revolution, where they are much nearer the pivot-center p^3 of the rocking head and cause the latter to rock in the opposite downward and backward (that is, down as to the arm p and backward as to the arm p') direction much faster than it was oppositely

turned, thereby producing, compared with the rearward movement of the carriage A' , a much more rapid forward movement for effecting the feed of the wire W , wherein there is very much less friction in the passage of the wire than in the barbing and straightening thereof, since inasmuch as the holding-dies, as will hereinafter more clearly appear, are open when the wire is fed, the feed is free and attended with very little friction to heat the parts, which may therefore be moved rapidly, while there is great friction in the operations of the barbing and straightening rollers, the heating effect of which is materially reduced by the comparatively slow movement with which their operations are produced. A further advantage afforded by the construction of this feature of my improved machine is due to the provision for adjusting the nut p^5 on its screw-stem p^4 nearer to or farther from the pivot-center of the head D to shorten or lengthen accurately in the desired degree the stroke of the arm D^2 , and through the latter that of the carriage A' , whereby while the extent of the reciprocal rotation of the washer y^2 in its guide-arm p remains necessarily unaltered, whatever the length of wire to be fed for each nail, the stroke of the carriage is longer or shorter, according to such length to be fed, which may be readily and quickly regulated without materially interfering with the operation of the machine by lowering or raising the nut p^5 on its screw-stem p^4 . These functions of my machine—namely, of producing rapid feed and comparatively slow straightening and barbing of the wire to be cut and formed into nails of any desired length—constitute a very important feature of my improvement, since thereby the machine may be operated to produce any desired length of nail without stoppage, as for cooling and without injury, for a comparatively long time, and I wish, therefore, to be understood as claiming this feature of my improvement as broadly as possible.

Adjacent to the inner end of the carriage A' , and supported on the bed A of the machine, is the cutting or cutting and pointing die mechanism, details of which are most clearly illustrated in Figs. 13 to 18, inclusive, of the drawings.

At opposite sides of a raised rigid rectangular portion A^2 , Fig. 6, of the bed A are the rectangular stems l' , provided with perforations l^5 , and extending transversely from the backs l^2 of their hollow heads l , formed with flanges l^3 , converging from the opposite edges of the said backs (see Fig. 14) and affording containing sockets for the cutting and pointing die-blocks and along the upper and lower outer edges of the stems l' , are formed offsets l^4 . Plates h , (see Fig. 17,) each perforated centrally through its body-portion, as shown at h^3 , are provided with lateral flanges h' , extending from one side, and top and bottom flanges h^2 , extending horizontally from the opposite side of the said body portion. The

plates *k* are adjusted against the stems *l'* of the heads *l*, with their flanges *k*² fitting into the offsets *l*⁴ of the stems, whereby the latter are embraced by the plates *k*, and the perforations *l*⁵ and *k*³ are caused to coincide with each other, and the flanges *k'* on the opposite outer sides of the plates form guide-recesses, into which fit offsets *i'* in the edges of the inner sides of bearing-plates *i*, Fig. 16, having central perforations *i*² coinciding with, but smaller in diameter than, the perforations *l*⁵ and *k*³, the bearing-plates *i* forming guides for the plates *k* and being provided at their bases with outward-extending perforated flanges *i*³, through which they are fastened to the base *A*. The parts *l*, *k*, and *i* are secured laterally together by bolts *i*⁴, extended through the aforesaid coincident perforations therein into the part *A*² of the bed *A*, of which perforations those in the parts *l'* and *k* being of greater diameter than the bolts, permit the parts *l* and *k* to be vertically adjusted (on loosening the set-screws *i*⁵, extending vertically through the stems *l'* against the bed *A*²) to a limited degree, which effects adjustment in a vertical direction of the cutting and pointing dies *F*, for which provision is also made to adjust them on the bed *A* nearer to and farther from the header by means of set-screws *i*⁶, extending through suitable nuts *i*⁷ into the ends of the stems *l'*.

G G are the blocks for supporting the cutting and pointing dies *F*, conforming in shape to that of their bearing-heads *l*, in which they fit in a manner to permit of their being therein readily reciprocated longitudinally. Each block *G* is provided toward the outer end and on its front side with a recess *h*, which may be formed by lugs *h'*, and it contains longitudinally extending inward from one end an opening or socket *h*² to receive the die *F*, and which is continued to the opposite end of the block as a threaded opening or nut for a set-screw *h*³, bearing against the inner end of the die (which is further held transversely by a set-screw *h*⁴) and by which to regulate the extent of projection thereof at the cutting end beyond the end of its block *G*. Between the recess *h* and the end of the die-block in which the die is contained a beveled backward-inclining opening *h*⁵, Fig. 18, is provided to extend from the face of the die-block into the socket *h*². This construction forms an important feature in my improved machine, since it renders without requiring the block *G* to be dislodged or even disturbed ready removal and insertion of a die *F* by advancing it till its rear end passes the corresponding beveled end of the opening *h*⁵, when (the set-screw *h*⁴ being loosened) it may be withdrawn lengthwise in an inclined position, as indicated by the dotted representation in Fig. 18, and it may obviously be also readily inserted and adjusted into position through the opening *h*⁵.

H H, Fig. 1, are bent levers fulcrumed at their bends upon posts *H'*, extending upward

from the bed *A* and flanking a laterally-upward-converging guide-channel *A*³, rising from the said bed. The shorter arms of the levers *h* are provided at their extremities with heads *g*, which enter the recesses *h* in the die-blocks *G*, and at the extremities of their longer arms the levers *H* are provided with rotary thimbles or rollers *g'*, which extend into and conform to the cam-grooves *C C'* between the collars *v* on the driving-shaft, and which, preferably, have the tapering form illustrated, whereby they may be continually rotated without slipping. For the purpose of strength the posts *H'* should be connected at their upper ends by a cross-bar *g*², affording at its center location for a horizontal socket *g*³, Fig. 8.

The upward-converging guide-channel *A*³, which should be lined along its sides with metal gibs *2 2* (see Fig. 8) contains so much of a sliding head *I'* as conforms in shape to it, but a portion of which projects upward in rectangular form beyond the guide-channel, forming offsets *3 3*, over which extend to confine the gibs *2 2* plates *4 4*, fastened to the said offsets. From the center of its forward end the head *I'* is connected pivotally, as in the manner clearly shown in Fig. 4, by a link *w'*, with the crank *w* on the driving-shaft *B*, and the head *I* extends from the rear end of the sliding head *I'*, being confined in a socket therein by a set-screw *5* and adjustable lengthwise by means of a nut *6*. On the outer end of the head *I* is a plate *I*², having screw-holes *I*³, Fig. 5, near its opposite ends, through which to secure flatwise against it a similar plate *I*⁴, having screw-holes *I*⁵ to coincide with the screw-holes *I*³, but of greater diameter than the latter to receive the securing-bolts *I*⁶. The plate *I*⁴ is on the end of a socket *I*⁷, in which is secured the heading-tool proper *I*⁸. By having the bolt-holes *I*⁶ larger than the bolt-holes *I*³, on loosening the bolts the heading-tool *I*⁸ may be readily adjusted in any direction transversely of the head *I* to bring it into alignment with and center it with reference to wire of any thickness being fed for the heading operation.

Adjacent to and just behind the cutting and pointing dies *F* are the vertically-extending holding or clamping dies *K* and *K'*, (see Fig. 9,) the first named being most clearly shown in Figs. 19 to 22, inclusive. The upper die *K* is vertically adjustable, but stationary in its adjusted position, while the lower *K'* is rendered elastically yielding vertically by suitable mechanism hereinafter described.

In the front side, centrally, of the raised portion *A*² of the bed *A* is a vertical rectangular guide-recess *f*, extending downward through the bed *A* and surmounted by an overhanging stationary nut *f'*. In the upper part of the recess *f* or part above the line of feed of the wire *W*, and extending to or nearly to the latter, is a rectangular plate *f*², having a stationary nut *f*³ projecting from its front

side, near the upper end a rigid guide-bearing f^4 , similarly projecting below the said nut, and near its lower end a rigid bearing f^5 , recessed vertically along its front side to admit the die K, and horizontally between its extremities to admit a clamp-socket f^6 , fastened in place by a screw f^7 , extending into it from the back of the plate f^2 and countersunk therein, the clamp having slight horizontal play to adjust it in an inward or an outward direction with reference to its bearing f^5 by turning the countersunk screw f^7 in the proper direction. The plate f^2 is secured in the recess f by means of a bolt f^8 , Fig. 4, passed horizontally into it from behind through an opening f^9 in the bed A² of somewhat greater diameter than the bolt to permit to the plate f^2 slight vertical play for its adjustment. A screw f^{10} extends in the nut f^3 through the guide-bearing f^4 , on opposite sides of which, respectively, it is provided with a jam-nut 8 and head 7. A cap-plate f^{11} projects from the top of the plate f^2 over the nut f^3 to afford a bearing for a set-screw f^{12} in the nut f' . The holding-die K, which I prefer to provide in rectangular form in cross-section, abuts at its upper end against the head 7, whence it passes through the clamp-socket f^6 , wherein it is held against falling by suitably tightening the screw f^7 .

By the foregoing construction the die K may readily to the slight extent required be adjusted vertically by manipulating the bolt f^8 and set-screw f^{12} to raise or lower the plate f^2 in the recess f , and removal or resetting of the die K may be readily performed on withdrawing the bolt f^8 to permit the plate f^2 to be withdrawn from the recess f and access to the clamp-screw f^7 to be had for loosening the die to enable it to be moved or removed.

The lower holding-die K' is supported in line with the die K (like which it is formed) on a plate e, confined to slide vertically in the lower part of the recess f, and having suitable bearings (which may be similar, as shown, to those on the plate f^2) for the die K', the supporting mechanism of which is sustained by a crank-arm e', (see Fig. 2,) having a stud e² on its under side entering an interposed concaved bearing-block e¹. The crank-arm e' projects from between the ends of a rock-shaft e³ below a socket e⁴ in the base of the bed A, containing a spring e⁵, bearing against a stud e⁶, extending into the socket from near the free end of the crank-arm.

An arm L', secured at one end to an end of the rock-shaft e³, extends along a side of the machine, with its opposite end carrying a roller e⁹ in contact with a cam L on the power-shaft B, having on its periphery three cam-surfaces d, d', and d'', straight, as shown, where they join each other to avoid pounding, the first being nearest the center B, the second farther, and the last farthest from the said center and operating, respectively, in the rotation of the driving-shaft by their successive engagement with the free end of the arm L'.

first to permit the die K' to be lowered to the lowest limit of its play by the action of the spring e⁵ against the arm e', and thereby fully "open" the holding-dies, then to raise the lower die K' far enough to cause it to clamp the wire between it and its companion die K with sufficient firmness to hold it against withdrawal by the friction upon it of the barbing and the straightening rollers in the backward movement of the carriage A', and, thirdly, to raise the said lower die still farther and clamp the wire with greater firmness, capable of withstanding the stroke of the header.

M, Fig. 10, is the reel for supporting the coil of wire to be fed to the machine. I prefer that the reel M shall involve the construction illustrated, though any other suitable form of reel may be used, and I do not wish to be understood as limiting my improved form of reel to any particular wire-nail machine. In fact, the downward inclination of the machine toward the carriage end thereof, if so constructed, as I prefer it shall be, would render the employment with it of my improved reel of less importance.

The reel M illustrated is designed to hold the coil of wire in place, and particularly to permit the coil, which is very heavy, to be readily adjusted in place upon it, and I therefore have it adjustable to a horizontal position to enable the coil of wire to be readily slipped over it by applying the coil while in a vertical position, and from the horizontal position of the reel it is readily adjustable to its normally-vertical position.

The construction of the reel involves a hub c', having a center post c and radially-extending arms c², which may be connected near their extremities by a hoop c³, and which support, near the hub, the vertical posts c⁴, forming, with the post c, the core for the coil of wire W. The posts c⁴ are connected in pairs near their upper ends, and thus braced by metal bars c⁵, and diagonally by bars c⁶, laterally from which project the studs c¹⁴, and which form a center bearing c⁷ for the upper end of the central post c, and the adjacent members of opposite pairs of the posts c⁴ are further interbraced by the bars c⁸. These latter afford, each at one end, with the adjacent end of a brace-bar c⁹, bearing for a journal c¹⁰, extending through the bifurcated upper end of a post, the journals supporting arms c¹⁰ normally extending horizontally, as shown by full lines, to form an upper confinement for the coil of wire, being held in such position by the studs c¹¹, entering sockets c¹² in the arms c¹⁰ near their inner ends. The arms c¹⁰ are adapted to be turned to extend lengthwise of the posts c⁴, when the reel is adjusted, to receive the coil into a horizontal position by turning its supporting-bar c¹¹ in its socket c¹² on a side of the bed A of the machine, and in which it may be secured by a spring-stud c¹³, passed transversely into it through the socket or by other suitable means.

The operation of the machine is as follows:

As already stated, the machine is illustrated with the operating parts in the relative positions they assume just after a section of wire W (which may previously have been formed by the machine into a nail) has been severed by the cutting and pointing dies F. These were actuated for the purpose by the action of the cams C C' on the shaft B upon the die-blocks G through the medium of the bent levers H, and the timing of the operations of the parts is such as to cause the severing to take place (slowly when the parts v' of the cams act against the rollers g') immediately upon the completion of the rapid feed, produced in the manner already described, through the media of the eccentric y on the power-shaft B engaging the angular rocking head D in a manner to cause the lever D² to move the carriage A' quickly forward and the (barbing) rollers n and o' to feed the wire. The shaft B has then brought the part d of the cam L against the roller on the arm L' to cause through the latter the rock-shaft e² and arm e', to permit lowering of the holding-die K', (thus freeing the feed-passage,) to be subsequently raised by the part d' to clamp the wire with sufficient firmness to hold it against the strain of the barbing and straightening operations of the mechanism on the slowly-receding carriage A', and the further effect of the rotating shaft B has been to advance the header toward the end of the wire to be upset. Further rotation of the power-shaft, besides causing the further separation of the cutting and pointing dies F and backing of the carriage A', will bring the part d² of the cam L against the arm L' to cause it to increase the clamping effect of the holding-dies on the wire while the header completes its stroke and forms the head.

A very important feature of my improvement, where it relates immediately to the operation of the cutting-dies, is that whereby strain is avoided of the arms H at their ends against the reciprocating heads G of the cutting-dies, it will be noticed, on reference to Fig. 1, that when the inner ends of the cutting-dies F are in the act of severing the wire, and to that end are brought closest together and are offering the greatest resistance to the arms H, the arrangement is such as to bring the inner edges of the heads g of the arms into alignment with the centers of the pivot-posts H', so that the heads g are never forced farther toward each other than to be brought into such alignment. Therefore there can be no wedging strain of the heads g in their sockets h', tending to fracture the heads G, as there would be were the heads g caused to pass such alignment in exerting the great severing strain to which they are subjected.

Provision for different degrees of the clamping effect of the wire by the holding-dies is advantageous in enabling strain on the machine to be regulated during its operation, according to requirement, and thus avoid-

ing excessive strain when not needed, which obviously reduces wear on the machine.

For the smaller sizes of wire the end of the lever L', having the roller e², may be adjusted with relation to the cam L by means of a suitable set-screw device A⁴, Fig. 2, thereby to regulate the play of the die K'. When the head has been formed in the advance movement of the header, (which is materially assisted by its weight when inclined, as shown in Fig. 4, in the direction of its advance movement,) and by the continued rotation of the shaft B the header retracted, the wire released from the effect of the part d² of the cam L, of which the shallowest part d is then in contact with the roller e², permitting the under holding-die K' to be separated to the farthest limit from its companion K, and the angular head D actuated (about twice as fast as in the backward straightening and barbing movement of the carriage A') to rapidly feed another length of the wire terminating in the already-formed head referred to, the cams C C' are again in position to actuate the dies F to sever gradually the length so fed and point it at its severed extremity.

As usual, a knock-off attachment N is provided to follow in its operation that of the cutting-dies. I form a knock-off or striker device N for my improved machine, preferably of the details shown, (say most clearly in Fig. 4,) and comprising a bar b, supported pivotally to extend lengthwise of the machine toward the cutting-dies on posts b' and longitudinally extensible, as by means of the rod b², inserted into its extremity and held by a set-screw b³. The knock-off tool proper a extends downward in line with the wire at the cutting-dies from a suitable support a³ on the extensible rod b², passing through a guide-socket a² on a rod a', supported and longitudinally adjustable and controlled by a set-screw a⁴ in the socket g³ at the center of the bar g², connecting the posts H'. The rod b is controlled to return the knock-off or striker device to its normal position by a spring a⁵, extending against it from the socket g³, and a cam b⁴, adjustably supported on the rod b near the shaft B is struck to actuate the knock-off by a finger b⁵ on the link w', arranged to be actuated by the shaft B just after it has produced the severing operation of the dies F.

The foregoing minute description is considered necessary to enable my improved machine and the manner of its operation to be clearly comprehended, owing to the somewhat intricate nature thereof. I do not, however, wish to be understood as intending to limit my invention to mere details of construction, as they may in various instances be changed without thereby departing from my invention.

What I claim as new, and desire to secure by Letters Patent, is—

1. In a wire-nail machine, the combination, with the rotary power-shaft, of a reciprocat-

- ing carriage suitably connected with the power-shaft and supporting wire straightening and feeding mechanism and reciprocating in the opposite directions by the rotation of the 5 shaft at different rates of speed—namely, slower for the straightening and faster for the feeding—with a varying stroke according to the length of wire to be fed, substantially as described.
- 10 2. In a wire-nail machine, the combination, with the rotary power-shaft, of a reciprocating carriage suitably connected with the power-shaft and supporting wire-straightening rollers, and wire barbing or feeding rollers 15 operated by the backward movement of the carriage, the said shaft in its rotation operating through the medium of its said connection with the carriage to reciprocate the latter in the opposite directions at different rates 20 of speed—namely, slower for the straightening and barbing operations and faster for the feeding—and with a varying stroke according to the length of wire to be fed, substantially as described.
- 25 3. In a wire-nail machine, the combination, with the bed A, of a rotary power-shaft, an angular rocking head D, pivotally supported at its angle and connected from its arm p with the power-shaft eccentrically thereof, 30 and a reciprocating carriage A', supporting the wire straightening and feeding mechanism and connected with the arm p' of the said head D, substantially as described.
4. In a wire-nail machine, the combination, 35 with the bed A, of a rotary power-shaft B, having an eccentric y near one end, an angular rocking head D, formed with an arm p, having a guide, and an arm p', and pivotally supported on the bed between the two said 40 arms, a washer y' in the guide of the arm p and connected with the eccentric y, a reciprocating carriage A', carrying the wire straightening and feeding mechanism at the rear end of the machine, a lever D², fulcrumed 45 between its extremities and engaging at one end with the said carriage, and a link D', connecting the said lever from its opposite end with the arm p' of the rocking head D, substantially as described.
- 50 5. In a wire-nail machine, the combination, with the bed A, of a rotary power-shaft B, having an eccentric y near one end, an angular rocking head D, formed with arms p and p', containing guides, and pivotally supported on the bed between the two said arms, 55 a washer y' in the guide of the arm p and connected with the eccentric y, a nut p³ on a screw p⁴ in the guide of the arm p', a reciprocating carriage A', carrying the wire straightening and feeding mechanism at the rear end of the machine and provided with 60 a hollow head m in a recess m', a lever D², fulcrumed between its extremities and engaging at one end with the head m, and a link D', connecting the said lever from its opposite end with the nut p⁵, substantially as described.

6. In a wire-nail machine, the combination, with the bed A, supporting the wire severing and heading mechanisms, of a reciprocating carriage A' and a wire-straightening attachment E for straightening the wire in a vertical direction, pivotally supported on the carriage and adjustable on its support through a vertical plane to different angles from its 75 normal perpendicular position, substantially as described.

7. In a wire-nail machine, the combination, with the bed A, supporting wire severing and heading mechanisms, of a reciprocating carriage A' and a wire-straightening attachment E, comprising a frame t, pivotally supported on the carriage to permit its adjustment by swinging it on its pivot from its normal perpendicular position through a vertical plane, and having journaled within it rollers s and s', one above the other, at opposite sides of the line of feed of the wire W, substantially as described.

8. In a wire-nail machine, the combination, 90 with the bed A, supporting wire severing and heading mechanisms, of a reciprocating carriage A', a wire-straightening attachment E, comprising a frame t, journaled on the carriage to permit its adjustment through a vertical plane and having journaled within it rollers s and s', one above the other in adjustable bearings s¹ and s², provided with means for adjusting them, a handle s³ on a supporting-journal of the frame t, and a vertically-disposed segmental rack s⁴, engaged by the handle, substantially as described.

9. In a wire-nail machine, the combination, with the bed A, supporting wire severing and heading mechanisms, of a reciprocating carriage A', supporting a pair of horizontally-disposed straightening-rollers q' at one side of the line of feed of the wire W, and at the opposite side thereof a similarly-disposed roller q on a sliding bearing q², having a rectangular opening q³ in its outer end, and an eccentric confined in the said opening and controlled from a handle q⁴, substantially as described.

10. In a wire-nail machine, the combination, 115 with the bed A, supporting wire severing and heading mechanisms, of a reciprocating carriage A', supporting a pair of horizontally-disposed straightening-rollers q' at one side of the line of feed of the wire W, and at the 120 opposite side thereof a similarly-disposed roller q in a sliding bearing q², having a rectangular opening q³ in its extension q⁴, a head q⁵, confined in the said opening and provided eccentrically with a pivot-pin q⁶, a handle q⁷ 125 for the head, and a horizontally-disposed segmental rack q⁸ for securing the handle, substantially as described.

11. In a wire-nail machine, the combination, 130 with the bed A, supporting wire severing and heading mechanisms, of a reciprocating carriage A', a wire-straightening attachment E for straightening the wire in a vertical direction, and comprising a frame t, journaled on

the carriage to permit its adjustment through a vertical plane, and having journaled within it rollers s and s' , one above the other, at opposite sides of the line of feed of the wire W , 5 and horizontally-disposed straightening-rollers, comprising a pair q' at one side of the said line of feed and an intermediate roller q at the opposite side thereof on a sliding bearing q^2 , and an eccentric engaging the sliding bearing q^2 and provided with a handle q^8 , 10 from which to control the adjustment of the roller q , substantially as described.

12. In a wire-nail machine, the combination, with the bed A , supporting wire severing and heading mechanisms, of a reciprocating carriage A' , provided with wire-straightening rollers and supporting in advance of the straightening-rollers a pair of horizontally-disposed barbing-feed rollers o , journaled 15 in slidably-adjustable bearings in a recess o^2 , formed transversely in the carriage-bed and terminating at its opposite ends in box-shaped bearings o^3 , having upward-projecting tongues o^4 , a confining-ring o^6 , surrounding 20 the said tongues o^4 , and set-screws o^7 , extended against the said sliding bearings through the ends of the bearings o^3 , substantially as described. 25

13. In a wire-nail machine, the combination, 30 with the bed A and rotary power-shaft B , supported thereon, of the vertical clamping-die K and vertically-reciprocating clamping-die K' , and a cam L , having differential peripheral cam-surfaces d , d' , and d^2 , straight or 35 substantially straight where they merge one into the other, thereby to avoid pounding, the differential cam-surfaces controlling the degree of clamping effect with relation to the line of feed of the wire W of the die K' 40 through suitable intermediate lever mechanism, substantially as described.

14. In a wire-nail machine, the combination, with the bed A , supporting a rotary power-shaft B , wire severing and heading mechanisms, 45 and a reciprocating carriage A' , carrying wire straightening and feeding devices, of a vertical clamping-die K , extending toward the upper side of the line of feed of the wire W , a vertically-reciprocating clamping-die K' 50 below the die K at the opposite side of the said line of feed, a rock-shaft e^8 , eccentrically from which the die K is supported, an arm L' , extending from the rock-shaft to the power-shaft B , and a cam L on the power-shaft 55 engaging with the arm L' and having the differential peripheral cam-surfaces d , d' , and d^2 , substantially as and for the purpose set forth.

15. In a wire-nail machine, the combination, 60 with the bed A , supporting a rotary power-shaft B , wire severing and heading mechanisms, and a reciprocating carriage A' , carrying wire straightening and feeding devices, of a stationary vertically-adjustable clamping-die K , extending toward the upper side of the 65 line of feed of the wire W , a vertically-reciprocating clamping-die K' below the die K at

the opposite side of the said line of feed, a rock-shaft e^8 , having an arm e' extending from it and supporting the die K' and elastically controlled by a spring e^5 near its free end, an arm L' , extending from the rock-shaft to the power-shaft B and provided with a roller e^9 , and a cam L on the power-shaft engaging with the roller e^9 and having the differential peripheral cam-surfaces d , d' , and d^2 , substantially as described. 75

16. In a wire-nail machine having the cutting-dies, their operating-levers, and the driving-shaft, the cams herein described, having 80 gradual and uniform increase in pitch, changing at a predetermined point on the cam to a slight pitch in the same direction and then gradually decreasing in pitch, whereby the operation of the cutting-dies in one direction 85 is first rapid and then slow to perform the cutting and severing operation at a slower speed than the remaining movement of the dies, substantially as described.

17. The combination of a severing-die F for 90 a wire-nail machine and a die-block G therefor, having a socket h^2 for the die, and an outward-flaring opening in its face leading into the die-socket, substantially as and for the purpose set forth.

18. The combination of a severing-die P for 95 a wire-nail machine, a die-block G therefor, having a socket h^2 for the die, and an outward-flaring opening in its face leading into the die-socket, a set-screw h^4 for controlling 100 the die in a transverse direction, and a set-screw h^8 , bearing against the rear end of the die, substantially as described.

19. A wire-nail machine comprising, in combination, a bed A , supporting the rotary power-shaft B , having a crank w between its extremities, a cam L near one end, provided with differential peripheral cam-surfaces d , d' , and d^2 , an eccentric y at its opposite end, and intermediate cams C and C' , an angular rocking head D , pivotally supported at its angle and having its arm p engaged by the said eccentric y through the medium of the sliding washer y^2 , a reciprocating carriage A' , supported at the rear end of the machine 115 and carrying straightening and feeding devices, a lever D^2 , engaging at one end with the carriage and connected from its opposite end by a link D' with the arm p' of the device D , a vertical clamping-die K , and a vertical 120 spring-controlled reciprocating clamping-die K' , a rock-shaft e^8 , having an arm e' , supporting the die K' , and an arm L' , extending from the said rock-shaft into engagement with the cam L , cutting-dies F , supported in reciprocating die-blocks G , and levers H , fulcrumed between their extremities and engaging at corresponding ends with the die-blocks, and provided at their opposite ends with rollers g' , engaging the cams C and C' , the whole being constructed and arranged to operate substantially as described. 125

20. In a wire-nail machine, the combination, with the bed A , supporting the power-shaft B ,

of a header comprising a reciprocating head I', having a head I extending from it and provided at its extremity with a plate I², having screw-holes I³, a plate I⁴, having screw-holes I⁶ 5 larger in diameter than the screw-holes I³ and bolted through said holes to the plate I², and a socket I⁷ on the plate I⁶ for the header-tool I⁸, substantially as described.

21. In a wire-nail machine, the combination, 10 with the bed A, supporting the power-shaft B, reciprocating carriage A', provided with the wire straightening and feeding devices, the header, clamping-dies, severing-dies engaged by the levers II, fulcrumed on posts II', and 15 means for actuating the said mechanism from the rotary power-shaft, all co-operatively arranged substantially as described, of a striker device N, comprising a pivotally-supported rod b, provided with an extension-rod b², carrying the knock-off tool a on a suitable support a³, guided in a socket a² on a rod a', supported and longitudinally adjustable in a 20 socket g³ on a cross-bar g², connecting the posts II', a spring a⁵, extending against the rod b, a cam b⁴, adjustably supported on the rod b near the shaft B, and a finger b⁵, supported on a link w', connecting the header with the power-shaft, the whole being con- 25

structed and arranged to operate substantially as described.

22. In combination with a wire-nail machine, a reel M for the supply-coil of wire W, having a core for the coil and supported on a suitable bar c¹¹, extending to the location for the reel from the machine and adjustably secured in a bearing c¹² on the frame A, to 30 permit the bar to be turned on its axis for adjusting the reel to a vertical or a horizontal position, substantially as described.

23. In combination with a wire-nail machine, a reel M for the supply-coil of wire W and formed with a central post c in a hub c', having radial arms c², supporting-posts c⁴, braced toward their upper ends, and arms c¹⁰, 35 pivotally supported on posts c⁴, and a bar c¹¹ for supporting the reel, extending to the location for the reel from the machine and adjustably secured to permit turning thereof on its axis at one end in a bearing c¹² on the frame A and secured at its opposite end to 40 the hub c', the whole being constructed and arranged to operate substantially as described.

JOSEPH VON SERKEY.
